GOLF BALL

Application filed March 11, 1930. Serial No. 434,895.

This invention relates to playing balls and more especially to golf balls.

A golf ball in order to meet the requirements of present day standards in the game of golf must be so constructed that it will give great distance when struck properly, that its flight will be true when struck properly and that the feel or "click" of the ball when struck by the club has those optimum 10 characteristics familiar to one skilled in the game. While golf balls capable of long and true flight when properly struck have been available heretofore, it has been difficult to obtain a ball having the proper feel or "click" 15 along with the other desired characteristics.

It is the object of this invention to obtain a novel golf ball and especially a novel golf ball center which when made into a golf ball will result in a ball having the characteristics 20 of long and true flight as well as having the optimum feel or "click". Also an object of this invention is to provide a novel center construction. Other objects and advantages of the present invention will appear from the 25 following detailed description taken in connection with the accompanying drawing.

Figure 1 is a cross section of a golf ball made according to the principles of this invention;

Fig. 2 is a cross section through a golf ball center made according to this invention; and

Fig. 3 shows the parts of the golf ball center in unassembled relation.

According to this invention, a golf ball center is made up of a plurality of parts, as shown in Fig. 3, that part designated by the numeral 1 being the pellet or pill or core of the center which preferably is spherical, although its shape may depart somewhat from 35 a ball, according to this invention. The core or pill or pellet 1 preferably is of a material moderately stiff although having flexibility in some degree and preferably contains compounding material which gives it considerable 40 density so that as much of the weight of the ball may be positioned as near the geometrical center of the ball as possible. However, this invention in its broadest aspect comprehends a core, pellet or pill 1 which 45 may be rigid or may be highly flexible and

which may be of small or great density and which may be resilient in varying degrees. The core 1 is preferably made of a suitable rubber compound although other materials may be employed, such as metals, celluloid, 55 gutta percha, etc.

Around the relatively rigid pill 1 are a number of shells or layers or sheaths 2, 3, 4 and 5, which preferably take the form of semi-spherical cups, as shown in Fig. 3, which fit together first over the pellet and then successively over each preceding sheath or layer. The shells, sheaths or layers 2, 3, 4 and 5 are 60 independent in the sense that they are not united and may slide one upon another.

The shells 2, 3, 4 and 5, while preferably made in halves, may be otherwise divided so long as they have the capacity for fitting over and around the pill or the preceding sheath. The number of shells or layers, as shown in 65 the drawing and as preferred, is four, although two or a greater number may be employed as desired. The shells are made of a size to fit snugly over one another with only slight clearance. The sheaths are preferably 70 made of a highly flexible and elastic material, such as a vulcanized rubber compound although the degree of flexibility and resilience of the material of the sheaths may be varied widely without departing from this invention.

The shells may all be of the same thickness, as shown in the drawing, although, if desired, the successive shells may be made 75 each of a different thickness without departing from this invention. The shells 2, 3, 4 and 5 when in assembled relation preferably 80 interfit so that cracks between the halves of each shell or sheath do not fall in the same plane and in so far as possible it is preferred to have the cracks between the halves of the 85 shells at right angles to each other or at least at widely divergent angles. However, the particular arrangement of shells in assembled relation may be widely varied within this invention.

In order to facilitate sliding motion between the various shells, it is preferred to coat all the surfaces of the shells, as well as the pellet 1, with a lubricant and it is also preferred to incorporate a lubricating ingredient 90 95 100

on the shells 2, 3, 4 and 5. While the presence of lubricants on the shells and in the material thereof is preferred, such lubricants are not necessarily essential and the invention may be practiced without them.

5 While the exact dimensions of the shells and of the pill 1 may be varied widely without departing from this invention, a suitable range of sizes has been found to be as follows: 10 Pill 1 of a diameter of approximately $\frac{5}{8}$ " ; the shells 2, 3, 4 and 5 each of a thickness approximating $\frac{1}{16}$ " and of an interior diameter of the shells such as to fit snugly over the preceding shell or over the pill. A satisfactory 15 composition of material for the shells has been found to be as follows:

	Ounces
Rubber	10
Balata	10
Sulphur	1
20 Zinc oxide	1
Reaction product of triethyl tri-methylene amine and zinc acetate	.40
Hard wood pitch	.18
25 Graphite No. 2	5

A satisfactory lubricating medium is flake graphite, although other media may be used.

The golf ball center in assembled form, as shown in Fig. 2, is then wrapped with strands 30 of elastic material, indicated at 6 in Fig. 1, over which winding is applied a cover 7. The winding 6 and cover 7 are of any conventional structure well known in the art.

While the exact action of the golf ball center herein disclosed is not known with certainty, yet without limiting the invention hereto, the following theory of action is advanced by way of explanation. It is believed that due to the ability of the shells 2, 3, 4 and 40 5 to slide over the pill and over one another, that when the ball is struck with the club the deformation which takes place in the ball due to the impact of the club is caused to proceed at a slower rate or to be taken up by the sliding and flexing action of the various shells in, perhaps, a manner similar to the action of the leaves of a spring. Regardless of whether this theory of operation is correct, the result attained by using the golf ball center of this 45 50 invention is a golf ball which when struck by a club has the optimum feel or "click" and that result is attained without sacrificing the accuracy and length of the flight of the ball.

While the invention has been described by 55 way of illustration, it is not intended so to limit the invention inasmuch as variations in the details thereof may be made without departing from the scope of the invention as defined in the following claims.

60 Having thus described my invention, what I claim and desire to protect by Letters Patent is:

1. A golf ball center having a pill, two or 65 more shells of resilient flexible material

around the pill, and a lubricant between the adjacent surfaces of the shells and the pill.

2. A golf ball center having a pill of resilient material, and two or more successive shells of resilient flexible material around 70 the pill, said material of the shells containing a lubricating ingredient.

3. A golf ball center having a pill, two or more shells of resilient flexible material around the pill, a lubricant between the adjacent surfaces of the shells and the pill, said material of the shells containing a lubricating 75 ingredient.

4. A golf ball comprising a core, a separate layer of resilient flexible material around the core, one or more successive separate layers of resilient flexible material around said first layer, a winding of elastic strands around the last layer, a cover over the winding, a lubricant between the adjacent surfaces of said layers and the core. 80

5. A golf ball comprising a core or nucleus containing weight imparting ingredients, a winding of vulcanized rubber thread, a plurality of shells of rubber composition intermediate said core and said winding containing a lubricating substance adapted to facilitate relative movement of the shells, and a cover over the thread winding. 85

6. A golf ball comprising a core or nucleus containing weight imparting ingredients, a winding of vulcanized rubber thread, a plurality of shells of rubber composition intermediate said core and said winding provided with a lubricant therebetween, and a 90 cover over the thread winding.

Signed at Providence, county of Providence, State of Rhode Island, this 8th day of March, 1930.

ALLEN G. McKINNON.
